UNITED STATES PATENT OFFICE.

EDWIN F. BOOTH, OF MILWAUKEE, WISCONSIN.

SPECIFICATION.

1,269,251.

Specification of Letters Patent. Patented June 11, 1918.

Application filed March 6, 1917. Serial No. 152,448.

To all whom it may concern:

Be it known that I, EDWIN F. BOOTH, a citizen of the United States, residing at the city of Milwaukee, county of Milwaukee, 5 and State of Wisconsin, have invented new and useful Improvements in Shirts, of which the following is a specification.

My invention relates to improvements in shirts. It is a well known fact that when 10 suspenders are dispensed with and a belt is used for supporting the trousers that shirts are liable to work upwardly from the trousers, and especially so when such shirts are made of silk or smooth material such as is 15 used in their manufacture.

The object of my invention is to provide a simple and efficient device which is permanently secured to the lower end of the shirt, and is adapted to prevent the same from 20 working upwardly.

The construction of my invention is explained by reference to the accompanying drawing, in which—

Figure 1 represents a perspective view 25 thereof, the limbs of the wearer being indicated by dotted lines.

Fig. 2 is a front view of the lower end of the shirt, provided with my improvements, and

Fig. 3 is a rear view of the construction shown in Fig. 2.

Like parts are identified by the same reference numerals throughout the several views.

Attention is called to the fact that the shirt is retained in its lower position by the members 2, 2, and that such members 2, 2 are formed integral with the rear of the shirt 3, and are both connected at their front ends 4, 4 with the front of the shirt 5, 5 upon the respective sides of the opening 6. The front ends of the members 2, 2 are connected with the respective sides of the shirt by a series of stitches 7, 7. The limbs of the wearer extend through the openings 8, 8, such limbs being indicated by dotted

lines in Fig. 1. The slit between the members 2, 2 extends upwardly to or near the belt or waist band of the trousers, whereby said members 2, 2 may be separated when necessary so to do without detaching the front ends 4, 4 from the front of the shirt.

It will be obvious that the respective members 2, 2 may be separated when necessary so to do, as shown in Fig. 2, between the points 9, 9.

I am aware of the fact that shirts have been previously held downward within the trousers or below the belt by a somewhat similar construction by a single member which is detachably connected with the front 60 of the shirt by buttons or other equivalent device, but such retaining device is not only liable to become detached but the wearer is liable to forget to button the same in place, while by forming such retaining device in two separate pieces and permanently securing them to the respective sides of the front as shown, he is enabled to attach the front ends thereof securely to the front of the shirt, as shown in Figs. 1 and 2.

Having thus described my invention what I claim as new and desire to secure by Letters Patent, is:—

In a garment of the described class, the combination with the front and rear parts 75 of a shirt, of two separate end members both end members being permanently connected at their respective ends to the front and rear members of said garment, said members being adapted to prevent a shirt from accidentally moving upwardly when worn, while they also permit the two opposing sides of both the front and rear of the garment to be moved apart as circumstances may require.

In testimony whereof I affix my signature 80 in the presence of two witnesses.

EDWIN F. BOOTH.

Witnesses:

O. C. WEBER,
A. J. MCKERHAN.
